[57] CLAIM

The ornamental design for a trowel holder for attachment to belt, as shown.

DESCRIPTION

FIG. 1 is a perspective view front view of the trowel holder showing my new design.

FIG. 2 is a front view thereof;

FIG. 3 is a right side view thereof;

FIG. 4 is a left side view thereof;

FIG. 5 is a rear view thereof;

FIG. 6 is a top plan view thereof; and

FIG. 7 is a bottom plan view thereof.

The broken line showing of a trowel in FIG. 1 is for illustrative purposes only and forms no part of the claimed design.
